LIPSTICK CONTAINER

Joseph A. Uva, Watertown, Mass.

Application December 15, 1950, Serial No. 13,446

Term of patent 14 years

(Cl. D86—10)

To all whom it may concern:

Be it known that I, Joseph A. Uva, a citizen of the United States of America, residing at Watertown, in the county of Suffolk and State of Massachusetts, have invented a new, original, and ornamental Design for Lipstick Container, of which the following is a specification, reference being had to the accompanying drawing, forming a part thereof.

In the drawing:

I claim:

The ornamental design for a lipstick container, as shown.

JOSEPH A. UVA.
